EX

OR D 14,981

No. 14,981 Apr. 29, 1884

UNITED STATES PATENT OFFICE.

JOHN C. MILLER, OF MERIDEN, CONNECTICUT, ASSIGNOR TO THE MERIDEN BRONZE COMPANY, OF SAME PLACE.

DESIGN FOR A SCONCE-FRAME.

SPECIFICATION forming part of Design No. 14,981, dated April 29, 1884.

Application filed March 22, 1884. Term of patent 7 years.

To all whom it may concern:

Be it known that I, JOHN C. MILLER, of Meriden, in the county of New Haven and State of Connecticut, have invented a new Design for a Sconce-Frame; and I do hereby declare the following; when taken in connection with accompanying drawing and the letters of reference marked thereon, to be a full, clear, and exact description of the same, and which 10 said drawing constitutes part of this specification, and represents a front or face view.

This invention relates to a design for that class of frames usually made from metal to receive a mirror, and from which arms project 15 to support candle-holders, commonly called a "sconce," the invention relating particularly to the configuration of the frame; and the invention consists in the configuration of the frame, as shown in the accompanying illustration and hereinafter described.

The frame represents a square base with a central round opening. At each angle an ornament projects, presenting a right-angular shape, the sides of which are parallel with the

corresponding sides of the frame, the said ornament extending onto the surface toward the center, the edge of these angle ornaments raised to form a panel on the surface, and on the surface of the panel a floriated tracery. 25

The ornamentation of the surface of the angle ornaments may be varied, as that particular ornamentation is no part of my invention, the essential feature of my invention being the square frame with right-angular-shaped projections at each angle of the frame, represented 30 35 as lying upon the surface of the frame, and as shown in the accompanying illustration.

I claim—

The design for a sconce-frame, consisting of the square base with right-angular projections 40 45 at each angle of the frame, represented as lying upon and extending from the surface of the frame, as described, and shown in the accompanying illustration.

JOHN C. MILLER.
